United States Patent Office

Des. 192,168
Patented Feb. 6, 1962

192,168

RELIGIOUS PLAQUE OR SIMILAR ARTICLE

William J. O'Shea, 16 Centennial Drive, Syracuse, N.Y.

Filed July 24, 1961, Ser. No. 66,021

Term of patent 14 years

(Cl. D29—23)

FIG. 1

FIG. 2

FIG. 3

I claim:

The ornamental design for a religious plaque or similar article, substantially as shown.
